UNITED STATES PATENT OFFICE

HENRY R. MILLER, OF BERNVILLE, PENNSYLVANIA, ASSIGNOR OF ONE-HALF TO
PAUL A. HOLZMAN, OF TULPEHOCKEN, PENNSYLVANIA

SWITCH

Application filed January 17, 1930. Serial No. 421,385.

This invention relates to a switch and has for its primary object the provision of a rotary type of switch including reciprocating contact elements cooperating with stationary actuators whereby rotary movement of the switch will be converted into reciprocating movements in the actuation of the switch.

An object of the invention is the provision of a switch structure including reciprocating contact elements enclosed by the component parts of the switch structure for minimizing arcing.

Another object of the invention resides in the novel construction of each contact element and its cooperative relation with contact rings whereby the contact rings may be electrically connected together in one position of the contact element and electrically disconnected in another position of the contact element.

A feature of the invention resides in the novel location of the actuators, the formation of the recesses contiguous to the contact element and the specific structural features of the contact element, which enables the switch device to function with a snap action to assure perfect electrical contact and minimizing of arcing.

Another feature of my invention resides in the simplicity of construction of component parts and the novel manner of assembly, which not only reduces production costs but assures perfect electrical connection between the parts resulting in long life.

Beside the above my invention is distinguished in the use of a rotor in which is slidably mounted a contact element for electrically connecting or disconnecting a pair of contact rings, the latter being directly connected with the electric circuit.

With these and other objects in view, the invention will be better understood from the following detail description taken in connection with the accompanying drawings where-

in:

Figure 1 is a front elevation of the switch.

Figure 2 is a vertical section on line 2-2 of Figure 1.

Figure 3 is a vertical section along line 3-3 of Figure 2,

Figure 4 is an enlarged sectional view adjacent the contact element,

Figure 5 is an enlarged sectional view adjacent the contact element illustrating the formation of the recess,

It will be noted that the invention consists basically of a rotor 1 and a switch device 2 directly carried thereby and co-functioning with stationary actuators 3.

The rotor 1 consists of a shaft 2 rotatably supported by the housing 3 and having one end portion 4 exteriorly arranged to have directly attached thereto the operating knob 5. Mounted on the shaft is a disc 6 directly carrying the metallic rings 7 and 8 that are insulated therefrom by the insulating bands 9. Slidably supported by the bands as well as the rings, is a switch device 2, shown in this particular instance as consisting of a contact element 10, preferably in the form of a pin of the required length to span the distance between the rings in one position of the contact element. Thus, it will be appreciated that the rings are electrically connected together. To interrupt the electrical connection between the rings I arrange upon one end of the pin or contact element 10, an insulating tip 11 so positioned that when the contact element is in its other position, the tip 11 will engage one of the rings and electrically disconnect the same from the other ring.

To accomplish manipulation of the contact element 10, in an economical manner, I have illustrated the actuators 3 in the form of metallic strips 12 having bowed extremities 13 that are slidably related with the contact rings and adapted to snap into engagement with the ends of the pin when the bowed extremities are aligned with the wedge shaped recesses 14 formed in the rings in alignment with the contact element 11. At-

ention is called to the fact that the recesses 14 are each provided with an inclined wall 15 so positioned that after the contact spring or actuator 3 snaps into engagement with the contact element 11 the inclined wall will automatically force the actuator from the recess in the movement of the rotor.

To complete the invention, I provide terminal strips or contacts 16 constantly bear-

ing upon the contact rings to convey current to and from the rings in a well known manner.

Attention is called to the fact that the correlation between the contact element, contact rings 7 and bands 9 is such that the contact element 10 is practically enclosed, thereby minimizing arcing, and to assure a more perfect contact the contact rings may be provided with yieldable contacts or wiper elements 17 that have a direct sliding engagement with the contact element 10.

In operation of the device, the knob 5 is given a partial rotation for giving arcuate movement to the rotor, this action bringing the contact element 10 into engagement with either one of the actuators 3 and due to the resilient action of the latter, the contact element 10 is snapped into either one of its two positions, depending upon which actuator engages the contact element. This snapping engagement of the actuator with the contact element throws the same in a rectilinear direction which causes the contact element to 25 metallicly bridge the distance between the rings as shown in Figure 2, or cause the same to move to its other position, whereby the contact 11 is brought into play for insulating one ring from the other and thereby destroying electrical connection between the rings.

In concluding, I wish to call attention to the simplicity of construction of the component parts of the invention and the mode of assembly which enables me to produce, not only a relatively low cost article, but one possessing a unique action brought about by the novel construction and arrangement of the contact element with relation to the rotor, which converts rotary motion of the latter 40 into reciprocatory movement of the former for opening and closing an electric circuit. It is of course to be understood that component parts of the invention may be redesigned and assembled in other relations than illustrated and therefore I do not desire to be limited in protection in any manner whatsoever except as set forth in the following claims.

What I claim is:

- 50 1. A switch comprising a rotor and a switch device carried solely by and having a reciprocatory relation with said rotor and adapted to be operated by the latter in the movement thereof.
- 55 2. A switch comprising a rotor, a knob for turning the rotor a contact element carried solely by and having a sliding relation with said rotor and means for actuating said contact element in the rotations of said rotor for opening and closing a circuit.
- 60 3. A switch comprising a rotor including metallic rings, a contact element slidably supported by said rotor to electrically connect and disconnect said rings and means ar-

ranged to operate said contact element in predetermined positions of said rotor.

4. A switch structure comprising a rotatably mounted disc, contact rings secured to but insulated from said disc, a contact element for electrical connection and disconnection with said rings, and stationary means arranged to reciprocate said contact element in the rotary movement of said disc.

5. A switch comprising a housing, a shaft journaled in the housing, an operating knob connected to said shaft, a disc mounted on said shaft, a pair of metallic rings supported by but insulated from said disc, a slidably mounted contact element for establishing electrical connection between the rings, and stationary members arranged to engage said pin and operate the same according to the rotary movement of said disc.

6. A switch comprising a housing, an operating shaft journaled in the housing, a disc mounted on the shaft, a pair of metallic rings mounted upon but insulated from said disc, a slidably mounted contact element for establishing electrical connection between said rings, said element including an insulating tip engaging one of the rings to interrupt electrical connection between the rings when the contact element is in a predetermined position, and stationary members arranged to periodically engage said contact element and move the same according to the rotary movement of said disc.

7. In a structure as described, a pair of contact rings and a contact element slidably related therewith consisting of a metallic pin of a length to span the distance between the rings and an insulating tip mounted upon the pin to electrically disconnect the rings when the pin is in a predetermined position.

8. In a switch structure, a pair of contact rings, a pin slidably mounted within the rings to electrically connect the same together when in a predetermined position and an insulating element mounted on said pin to electrically disconnect the rings when the pin is in its other position.

9. In a switch structure, a pair of contact rings, a pin slidably mounted within the rings to electrically connect the same together when in a predetermined position and an insulating element mounted on said pin to electrically disconnect the rings when the pin is in its other position, and snap elements arranged to have a snapping engagement with said pin in predetermined positions of said pin.

10. In a switch structure, a pair of contact rings insulated from each other, a metallic contact pin slidably supported by said rings, to establish electrical connection therebetween an insulating tip upon one end of the pin to break electrical connection between the rings when the pin is in a predetermined

position, said rings having wedge shaped recesses aligning with said pin and spring actuators mounted in stationary positions relative to the rotary action of said rings to 5 periodically snap into engagement with said pin for moving the same into either of its two positions.

In witness whereof I have hereunto set my hand.
